TOY FIGURE

Joseph Anello, 1325 Richard Drive, Cahokia, Ill.

Filed Sept. 7, 1965, Ser. No. 86,870

Term of patent 7 years

(Cl. D34—2)

FIG. 1

FIG. 2

FIG. 3

FIG. 1 is a front elevational view of a toy figure embodying the present design.

FIG. 2 is a top plan view thereof.

FIG. 3 is a bottom view thereof.

FIG. 4 is a side view thereof, some of the fibers covering the exterior surface being shown removed for illustrative purposes only.

I claim:

The ornamental design for a toy figure, substantially as shown and described.
